ELECTRIC CHAIN HOIST

Irving R. Metcalf and George E. Bock, Chicago,
Ill., assignors to Whiting Corporation, Harvey,
Ill., a corporation of Illinois

Application March 31, 1947, Serial No. 738,430

11 Claims. (Cl. 254—168)

1

The present invention relates generally to electric chain hoists. More particularly the invention relates to that type of hoist which is adapted to be hung or suspended from an elevated or overhead support and as its principal components or parts comprises: (1) a frame which serves as a supporting instrumentality and has an upstanding hook for attachment to the overhead support; (2) a reversible electric motor which is mounted on the frame in such manner that the armature shaft thereof extends horizontally when the hoist is in its normal or operative position; (3) a sprocket which is mounted rotatably on the frame and is connected for drive by the armature shaft of the motor by way of speed reducing gearing; (4) a roller chain which has one end thereof anchored to the frame at a point adjacent the sprocket and its other end provided with a hook for attachment to the load to be hoisted and is trained around the sprocket to the end that when the sprocket is driven in one direction the hook is raised and when the sprocket is driven in the opposite direction the hook is lowered; (5) a reversing switch which serves to control the supply of current to the electric motor; (6) a brake which operates to lock the sprocket against rotation when the reversing switch is in its neutral or off position; and (7) a manually operable control mechanism which is operatively connected to the switch and the brake, comprises a centrally fulcrumed lever and operates when tilted in either direction from a normal horizontal position to shift the switch into one of its operating positions and at the same time release the brake.

One object of the invention is to provide an electric chain hoist of this type which is an improvement upon, and has certain inherent advantages over, previously designed hoists of the same general character and is characterized by a novel arrangement of parts whereby compactness, high efficiency and lightness of weight are obtained.

Another object of the invention is to provide an electric chain hoist of the type under consideration in which the electric motor is disposed on one side of the frame and the gearing, the reversing switch, the brake and the manually operable control mechanism are all mounted on the other side of the frame in order that the hoist as a whole when suspended by the hook on the frame is properly balanced without the necessity of employing a counterweight.

Another object of the invention is to provide an electric chain hoist of the aforementioned type and character in which the gearing whereby the

2

sprocket is connected for drive by the armature shaft of the motor consists of a first worm and worm wheel and a second worm and worm wheel and is self locking or irreversible in order that the load on the chain hook remains stationary in the event of failure of the brake or manual release of the brake during stoppage or interruption in the supply of electric current to the motor. Another object of the invention is to provide an electric chain hoist in which the brake is arranged and constructed in a novel manner and the brake and reversing switch are disposed in close proximity to, but outwards of, the housing for the gearing between the armature shaft and the sprocket and are housed within a readily removable sheet metal shell.

Another object of the invention is to provide an electric chain hoist of the last mentioned character in which the manually operable control mechanism is constructed and arranged in a novel manner and is for the most part housed or disposed within the sheet metal shell.

Another object of the invention is to provide an electric chain hoist of the aforementioned type which, if desired and without rerigging or rearrangement of parts, is capable of being supported from above by the hook on the chain and when so supported is adapted to travel up and down the chain and support the load by way of the hook on the frame.

A further object of the invention is the provision in connection with an electric chain hoist of the last mentioned character, of a roller which is rotatably mounted on the frame adjacent the point where the chain is anchored and serves when the hoist is used while supported on the hook on the chain to guide the portion of the chain which is in loop form and extends between the anchored chain end and the sprocket.

A still further object of the invention is to provide an electric chain hoist which is generally of new and improved construction, effectively and efficiently fulfills its intended purpose and, due to its design and construction, occupies but a comparatively small space and may be manufactured or fabricated at a comparatively low cost.

Other objects of the invention and the various advantages and characteristics of the present electric chain hoist will be apparent from a consideration of the following detailed description.

The invention consists in the several novel features which are hereinafter set forth and are more particularly defined by claims at the conclusion hereof.

In the drawings which accompany and form a

part of this specification or disclosure and in which like numerals of reference denote corresponding parts throughout the several views:

Figure 1 is an end view of an electric chain hoist embodying the invention, the view being toward or in the direction of the end that is opposite the electric motor and has the readily removable sheet metal shell for housing the reversing switch, the brake and the manually operable control mechanism;

Figure 2 is a vertical transverse section illustrating in detail the construction and design of the hook equipped frame;

Figure 3 is a vertical longitudinal section;

Figure 4 is a vertical transverse section on the line 4—4 of Figure 3;

Figure 5 is a side elevation, certain parts being broken away and other parts being shown in section for purposes of illustration;

Figure 6 is a vertical transverse section taken on the line 6—6 of Figure 5 and illustrating in detail the construction, design and arrangement of the gearing for driving the sprocket from the electric motor;

Figure 7 is an enlarged vertical transverse section taken on the line 7—7 of Figure 5 and showing the construction of the brake for locking the sprocket against rotation when the reversing switch is in its neutral or off position;

Figure 8 is an enlarged vertical transverse section taken on the line 8—8 of Figure 5 and illustrating the construction and design of the manually operable control mechanism;

Figure 9 is a vertical longitudinal section on the line 9—9 of Figure 8;

Figure 10 is a section taken on the line 10—10 of Figure 7 and showing in detail the construction and design of the reversing switch;

Figures 11 and 12 are vertical transverse sections taken respectively on the lines 11—11 and 12—12 of Figure 10; and

Figure 13 is a vertical transverse section showing the hoist in its inverted position wherein it is supported by the hook on the chain.

The electric chain hoist which is shown in the drawings constitutes the preferred form or embodiment of the invention. It is adapted, as well understood in the art, to be hung or suspended from an overhead support and serves as an instrumentality or medium for hoisting a load. As its main or principal parts the hoist comprises a frame 15, an electric motor 16, a sprocket 17, a roller chain 18, a reversing switch 19, a brake 20, and a manually operable control mechanism 21 for the switch and brake.

The frame 15 serves as a supporting structure for the other parts of the hoist and has associated with it a housing 22. It is preferably in the form of a one-piece steel casting and consists of a vertically extending wall 23, an upper arcuate wall 24, and a lower arcuate wall 25. The vertically extending wall 23 of the frame has the two arcuate walls 24 and 25 mounted on one side thereof, as best shown in Figures 2, 3, 4 and 13, and has on its other side an integral diagonally extending pad-like enlargement 26. The upper arcuate wall 24 extends through an arc of approximately 280° and is arranged so that the ends thereof are at the bottom portion of the frame 15. The lower arcuate wall 25 extends throughout an arc of approximately 135° and is located between the ends of the upper arcuate wall 24. It has a materially less radius than the upper arcuate wall and partially surrounds, and serves as a chain guide instrumentality for, the sprocket

17. Associated with the frame 15 is an upstanding hook 27 and this is adapted for attachment to the overhead support (not shown) and serves to suspend the hoist from the support. The shank of the hook extends through, and is rotatably mounted in, a tubular boss 28 which is formed integrally with, and depends from, the upper central portion of the upper arcuate wall 24 of the frame. A nut 29 is mounted on the lower end of the shank and coacts with a shoulder 30 to hold the hook 27 against vertical displacement with respect to the frame 15 while at the same time permitting the hook to swivel an anti-friction thrust type bearing 31 is interposed between the nut 29 and the lower end of the boss 28, as shown in Figure 3. The hook 27 is so positioned with respect to the center of mass of the hoist that when the hoist is suspended by the hook it is truly balanced both horizontally and longitudinally, as shown in the drawings.

The housing 22 is located on the side of the frame 15 that has the enlargement 26. Preferably it is in the form of a one-piece casting and consists of a vertically extending inner end wall 32, a vertically extending outer end wall 33 and a continuous side wall 34. The inner end wall 32 is elliptical and fits flatly against the vertically extending wall 23 of the frame 15. When the hoist is in its normal or operative position wherein it is suspended by the hook 27 the major axis of the inner end wall 32 extends horizontally. The central and lower portions of the inner end wall 32 have formed therein a diagonally extending opening 35 and this is shaped conformably to, and has disposed therein, the enlargement 26 on the vertically extending wall 23 on the frame 15. Bolts 36 extend through the walls 23 and 32 and serve to secure the housing 22 in fixed relation with the frame 15. The vertically extending outer end wall 33 is spaced outwardly from the inner end wall 32 and defines with the latter and the continuous side wall 34 a compartment 37 which is partially filled with any suitable lubricant and has disposed therein certain hereinafter described gearing for driving the sprocket 17 from the electric motor 16. The continuous side wall 34 extends between, and is connected to, the two end walls 32 and 33 and is shaped, so far as cross section is concerned, as shown in Figure 6. Lubricant is introduced into the compartment 37 by way of a screw threaded hole 38 which is formed in the side wall 34 of the housing 32 and is normally closed by a screw plug 39. A horizontally and outwardly extending web 40 is connected to one side of the housing side wall 34 and a pair of spaced apart upwardly and outwardly extending webs 41 is connected to the other side of the side wall 34. The outer edges of these three webs are straight and, as shown in Figure 6, are aligned with the adjacent portions of the edge of the elliptical inner end wall 32 of the housing 22.

The electric motor 16 is of the reversible variety. It is located adjacent the side of the frame 15 that has the arcuate walls 24 and 25 and consists of a cup-shaped casing 42, field windings 43 and an armature (not shown). The side wall of the casing is aligned with, and has the same radius as, the upper arcuate wall 24. It is connected to the last mentioned wall by way of a tongue and groove pilot variety connection 44. Bolts (not shown) serve removably to connect the casing of the reversible motor 16 to the arcuate wall 24. The field windings of the motor are suitably mounted within the side wall

of the casing 42 and surround the armature. The latter is mounted on one end of a horizontally extending shaft 45. The central portion of the shaft extends through a hole 46 in the central portion of the vertically extending wall 23 of the hoist frame 15 and is rotatably supported by way of a ball bearing 47, the outer race of which fits snugly within the hole 46. A conventional lubricant seal 48 surrounds the central portion of the shaft and serves to prevent leakage of lubricant past the hole 46 and the ball bearing 47. The other end of the shaft 45, i. e., the end that is opposite to that to which is applied the armature of the electric motor 16, extends through a hole 49 in the outer end wall 33 of the housing 22 and is rotatably supported by way of a ball bearing 50, the outer race of which fits snugly within the hole 49. A lubricant seal 51 is disposed outwards of the ball bearing 50 and serves to prevent lubricant from flowing from the compartment 37 through the hole 49. As hereinafter described the motor 16 is controlled by the reversing switch 19.

The sprocket 17 is located beneath one side of the armature shaft 45. It is partially surrounded by the lower arcuate wall 25 of the frame 15 and is keyed or otherwise fixedly secured to one end of a horizontally extending shaft 52. Such shaft is in parallel relation with the armature shaft 45 and is disposed for the most part in the compartment 37 within the housing 22. The end of the shaft 52 to which is applied the sprocket 17 extends through a circular hole 53 in the lower portion of the vertically extending wall 23 of the frame 15 and is rotatably supported by way of a ball bearing 54, the outer race of which fits snugly within the hole 53. A lubricant seal 55 is located in the outer end of the hole 53 and serves to prevent leakage of lubricant past the ball bearing 54. The other end of the shaft 52 is rotatably supported by way of a ball bearing 56, the outer race of which fits snugly within a circular recess 57 in the lower portion of the outer end wall 33 of the housing 22. The sprocket 17 is driven from the electric motor 16 by way of gearing. The latter is disposed wholly within the compartment 37 in the housing 22 and consists of a worm 58, a worm wheel 59, a shaft 60, a worm 61 and a worm wheel 62. The worm 58 is formed integrally with that portion of the armature shaft which extends between the ball bearings 47 and 50, meshes with, and serves to drive, the worm wheel 59. The latter is keyed, splined or otherwise fixedly secured to one end of the shaft 60. The latter, as shown in Figure 6, extends diagonally and has the upper end thereof supported rotatably by way of a ball bearing 63 and its lower end rotatably supported by way of a ball bearing 64. The worm gear 59 is applied to the upper end of the diagonally extending shaft 60. The outer race of the ball bearing 63 fits snugly within a circular hole 65 in the top portion of the housing side wall 34 and the outer race of the ball bearing 64 fits snugly within a circular hole 66 in the lower portion of the housing side wall. The hole 65 is covered by a removable cap 67 and the hole 66 is covered by a removable cap 68. The worm 61 is formed integrally with the lower end of the diagonally extending shaft 60 and meshes with, and serves to drive, the worm wheel 62. The latter is connected by way of splines to the central portion of the horizontally extending shaft 52 and is held against lateral displacement by way of a pair of sleeves 69.

Such sleeves are located on opposite sides of the worm wheel 62 and have the outer ends thereof in abutment with the inner races of the two ball bearings which serve rotatably to support the shaft 52. When the motor 16 is driven in one direction the aforementioned gearing consisting of the worm 58, the worm wheel 59, the shaft 60, the worm 61 and the worm wheel 62 is driven in one direction, and when the electric motor is driven in the reverse direction the gearing is reversely driven. The angle of the helix of the worm 61 is such that the gearing for driving the sprocket from the electric motor is self-locking or irreversible. As a result of this the sprocket 17 is positively held against rotation in either direction when the motor is at rest.

The roller chain 18 is of conventional or standard construction and is trained around the sprocket 17, as best shown in Figures 2, 3 and 13. One end of the chain is provided with a swivel type load receiving hook 70. The other end is pivotally connected to a horizontally extending anchor post 71 by way of a pair of links 72. As shown in Figure 4, the post 71 is located in side by side relation with the sprocket 17 and is connected to a boss on the lower portion of the vertically extending wall 23 of the frame 15. When the sprocket 17 is driven in one direction the hook 70 is raised and when the sprocket is reversely driven the hook is lowered. It is contemplated that in most instances the hoist will be supported from above by way of the upstanding hook 27 on the frame 15. When so supported the portion of the chain 18 that is between the sprocket 17 and the anchor post 71 hangs downwards in the form of a loop, as shown in Figure 2. When the hook is lowered the loop decreases in length and when the hook is raised the loop increases in length. It is also contemplated that in certain instances the hoist, instead of being supported from above by the upstanding hook 27 on the frame 15, will be supported by the chain hook 70, as shown in Figure 13. When so supported the hook 27 is adapted to be connected to the load and in connection with operation of the motor the hoist travels up the chain or down the chain, depending upon the direction of drive of the motor. In order to guide that portion of the chain that extends between the anchor post and the sprocket to and from the sprocket when the hoist is in, what may be termed, its inverted position wherein it is supported from above by the chain hook 70, a roller 73 is provided. This roller is substantially the same in diameter as the sprocket and is mounted for free rotation on the anchor post 71. It is disposed in the same plane as the sprocket 17 and is straddled by the links 72 which serve, as heretofore pointed out, to connect one end of the chain 17 to the anchor post. A cap screw 74 is applied to the outer end of the anchor post 71 and serves to hold the two links 72 and the roller 73 against outward displacement with respect to the anchor post. When the hoist is manipulated into its inverted position and supported from above by the chain hook the links 72 automatically swing downwards into the position shown in Figure 13 and the chain extends over the roller and under the sprocket. As shown in Figures 2 and 13, the sprocket 17 is so positioned or arranged that the portion of the chain that is between the sprocket and the chain hook is in alignment with the shank of the hook 27. A stripper 75 is fixedly connected by way of bolts

16 to the bottom or lower portion of the vertically extending wall 23 of the frame 15. It is so arranged that when the hoist is suspended from above by the hook 27 it underlies the sprocket 17.

The reversing switch 19 is disposed at one side of the housing 22 and underlies the web 40. It serves to control the supply of current to the electric motor 16 and consists of a plurality of rotary contacts 77, a rectilinear series of equidistantly spaced apart contact fingers 78 and an opposed rectilinear series of equidistantly spaced apart fingers 79. The rotary contacts 77 are mounted on a horizontally extending rock shaft 80, as best shown in Figures 10 and 11. Such shaft is disposed in parallel relation with the armature shaft 45 of the electric motor 16 and is supported rotatably by three spaced apart up-standing stamped metal plates 81, 82 and 83. The latter extend transversely of the armature shaft and have aligned circular holes in the lower portions thereof. A horizontally extending tube 84 extends through these holes and is fixedly secured to the hole defining portions of the plates by drive or press fits in order that the plates and the tube are in rigid relation. The central portion of the tube fits against the adjacent portion of the side wall 34 of the housing 22 and is clamped in place by way of a clamp plate 85, one end of which is bent into semi-circular form and partially surrounds the central portion of the tube 84 and the other end of which is connected to a lug 86 on the housing side wall 34 by way of a clamp bolt 87. When the clamp bolt is loosened so as to release clamping pressure on the tube the plates 81, 82 and 83 may be swung downwards away from the housing side wall into a position wherein the reversing switch is readily accessible for inspection or assembly purposes. The normal position of the plates 81 and 82 is adjacent the housing side wall. The inner end of the tube 84 extends through a slot 88 in the elliptical inner end wall 32 of the housing 22 and terminates adjacent one end of the lower arcuate wall 25 of the frame 15. The other or outer end of the tube 84 projects a comparatively small distance beyond or outwards of the outer end wall 33 of the housing 22. The plate 81 is located adjacent the elliptical inner end wall 32 of the housing and the plate 82 is located adjacent the outer end wall 33 of the housing. The third plate, i. e., plate 83, is located directly inwards of the outer end of the tube 84. The upper portions of the three plates are provided with aligned bearings 89 in which the rock shaft 80 is journalled. Suitable and properly located collars on the rock shaft serve to hold the latter against axial displacement with respect to the plates 81, 82 and 83. The rotatable contacts 77 of the reversing switch are mounted on the portion of the rock shaft that is between the plates 81 and 82. The contact fingers 78 are located on the inner side of the rock shaft and the lower ends thereof are suitably connected to a bar 90 of insulating material. The other contact fingers, i. e., the contact fingers 79, are located adjacent the outer side of the rock shaft and have the lower ends thereof suitably secured to a bar 91 of insulating material. The bars 90 and 91 are disposed in opposed and parallel relation and have the ends thereof secured in clamped relation against the central portions of the side edges of the plates 81 and 82 by way of bolts 92. The arrangement of the rotary contacts 77 is such that when the rock shaft 80 is rocked in one direction from a neu-

tral position the motor is driven in one direction and when the rock shaft is rocked in the opposite direction from a neutral position the motor is driven in the opposite direction. Current under control of the reversing switch 19 is supplied to the electric motor 16 by way of a plurality of conductors (not shown). Such conductors lead to the reversing switch and extend through a sheath 93, one end of which is connected by an elbow 94 to the elliptical inner end wall 32 of the housing. When the rock shaft is in its neutral or so-called off position no current is supplied to the motor. The rock shaft is urged into its neutral or off position by way of a device consisting of a helical spring 95 and an arm 96. The spring encircles or surrounds a bushing 97 which is connected to the arm. The ends of the spring 95 project upwards in spaced apart relation and have the upper ends thereof disposed in notches 98 in the sides of a lug 99. The latter is formed integral with and extends outwards at right angles to the upper end of the plate 82. The spring 95 is loaded so that the ends thereof press inwards against the sides of the lug 99. The arm 96 is fixedly connected to, and extends radially from, the central portion of the rock shaft and is provided at its outer end with a right angle lug 100 which underlies the lug 99 and is disposed between the ends of the spring 95. When the rock shaft 80 is rocked in one direction the lug equipped arm 96 distends or shifts laterally one end of the spring. When the rock shaft is rocked in the opposite direction the lug equipped arm shifts laterally towards the other end of the spring. As a result of the action of the ends of the spring the rock shaft is urged into its neutral or off position wherein the rotary contacts 77 are out of engagement with the contact fingers, as shown in Figure 11. The plate 83 which, together with the plates 81 and 82, serves to support the reversing switch 19 has an upwardly extending extension 101 which is disposed a comparatively small distance in front of the vertically extending outer end wall 33 of the housing 22. As shown in Figure 8 the two corner portions of this extension are provided with slots 102 through which normally extend the outer ends of a pair of horizontally extending studs 103. The inner ends of the studs are connected to the housing end wall 33 and the outer end of the studs are provided with fixed collars 104 and nuts 105. The collars abut against the inner surface of the extension 101 of the plate 83 and the nuts 105 fit against the outer surface of said extension and are adapted when tightened to clamp the notched corner portions of the extension against the collars 104. The notches are so arranged and shaped that when the nuts 105 are released after loosening of the clamp bolt 85 the plate 83 is free so that it may be swung laterally and downwards with the plates 81 and 82 in order to provide access to the reversing switch.

The brake 20 serves immediately to stop the electric motor 16 when the reversing switch is shifted to its neutral or "off" position and when operative locks the sprocket 17 against rotation in either direction. It is disposed outwards of the vertically extending outer end wall 33 of the housing 22 and comprises a cup shaped drum 106, a brake disc 107 and a brake band 108. The drum 106 is in the form of a sheet metal stamping and consists of a vertically extending circular end wall 109 and a cylindrical side wall 110. The end wall is disposed in concentric relation with the armature shaft 45 and has a central

hole through which the exposed outer end of the armature shaft extends. It fits flatly against the housing end wall 33 and is fixedly secured to the latter by way of bolts 111. As best shown in Figure 5 the drum 106 is disposed directly inwards of the extension 101 of the plate 83. The cylindrical side wall 110 of the drum 106 is connected to the margin of, and projects outwards from, the end wall 109. It surrounds the brake disc 107 and has adjacent the outer end of the rock shaft 80 a cutout 112. The brake disc 107 is keyed or otherwise fixedly secured to the outer exposed end of the armature shaft and is disposed in concentric relation with, and spaced a small distance from, the side wall 110 of the cup shaped drum 106. The brake band 108 surrounds the brake disc 107 and is arranged so that the ends thereof are disposed adjacent the cutout 112 in the cylindrical side wall of the drum. As shown in Figure 7 the ends of the brake band are doubled back so as to extend around the intermediate connecting parts of a pair of spaced apart U-shaped brackets 113. Such brackets are welded or otherwise rigidly connected to the doubled back ends of the brake band. They are spaced apart a distance less than the length of the cutout 112 and carry horizontally extending pins 114. The ends of the pins extend through circular holes in the side legs of the brackets 113. Two pairs of coacting toggle links 115 serve operatively to connect the brackets 113. The inner ends of the links 115 are pivotally connected together by way of a pin 116 and the outer ends of the links have holes through which the ends of the pins 114 extend loosely. The toggle links 115 are at all times disposed at an angle less than 180°. They are positioned so that the inner ends thereof are away from the brake disc 107. A pair of helical tension springs 117 serve to urge together the brackets 113 in order to cause the brake band 108 to contract around the brake disc 107. The springs are located outwards of the toggle links 115 and have the ends thereof applied to the ends of the pins 114. When the inner ends of the toggle links are urged towards the brake disc the brackets 113 are forced apart against the tension of the springs 117 and result in the brake band being expanded out of engagement with the brake disc and into abutting relation with the inner periphery of the cylindrical side wall 110 of the drum 106. When the inner ends of the links are released so that the springs 117 effect contraction of the brake band around the brake disc while the disc is rotating in one direction one of the brackets 113 strikes against the adjacent end of the cutout 112 and so anchors the adjacent end of the brake band to the drum that the band effects the desired braking of the disc. When the springs urge together the two brackets while the brake disc is reversely driven the other bracket strikes against the adjacent end of the cutout 112 and so anchors the connected end of the band to the drum that the brake effects braking of the disc. When the brake is applied or rendered operative the shaft 45 and the motor armature are brought to rest. Release of the brake frees the shaft 45 so that it together with the motor armature is capable of rotating. An actuator block 118 and a U-shaped bracket 119 operate automatically to release the brake when the rock shaft 80 is rocked in either direction from its neutral or "off" position in order to effect drive of the motor. The actuator block 118 forms a part of the portion

of the rock shaft that is disposed between the plates 82 and 83 and hence rotates or rocks conjointly with the rock shaft. The bracket 119 is located between the actuator block 118 and the inner ends of the toggle links 115 and is arranged so that the intermediate part thereof is in the path of, and engaged by, the actuator block 118 when the latter is rotated in either direction in connection with closing of the reversing switch. The side legs of the bracket 119 extend in the direction of the brake disc and have aligned circular holes therein through which extend the ends of the pivot pin 116. When the rock shaft is rocked so as to effect closing of the switch the actuator block 118 moves into engagement with the intermediate connecting part of the bracket 119 and operates through the medium of such bracket and the toggle links 115 to shift apart the brackets 113 and thus release the brake. The actuator block is so shaped and arranged that it effects release of the brake regardless of the direction of rocking of the rock shaft 80. In other words, due to the specific design and arrangement of the actuator block 118, release of the brake is effected automatically when the rock shaft is rocked in either direction with respect to its neutral or "off" position.

The manually operable control mechanism 21 for the reversing switch 19 and the brake 20 is located outwards of the plate 83 and consists of a centrally fulcrumed or first class lever 120 and three gear segments 121, 122 and 123. The lever 120 normally extends horizontally and has the ends thereof bent outwards at right angles to form forwardly extending ears 124. The central portion of the lever 20 is rotatably mounted about the central portion of a horizontally extending pin 125. Such pin is disposed for the most part outwards of the plate 83 and has the inner end thereof welded or otherwise fixedly secured to the extension 101 of said plate. The apex portion of the gear segment 121 fits against and is welded to the central portion of the lever 120 in order that said gear segment 121 rocks conjointly with the lever. The gear segment 122 has one portion thereof in mesh with one portion of the gear segment 121 and has its apex portion fixedly connected to one end of a horizontally extending shaft 126. Such shaft extends completely through the tube 84 and is journaled in bearings 127 in the ends of the tube. The other end of the shaft 126 projects beyond the lower arcuate wall 25 and is provided with a radially extending stop finger 128, the purpose of which is described hereafter. The gear segment 123 meshes with another portion of the gear segment 122 and has its apex portion suitably fixedly connected to the outer end of the rock shaft 80. When the lever 21 is rocked in one direction it operates through the medium of the three gear segments to rock the rock shaft in one direction and when the lever is rocked in the opposite direction it operates through the medium of the gear segments reversely to rock the rock shaft. Rocking of the lever is effected by way of a pair of depending side by side pull cords 129. The upper ends of these cords are connected by snap hooks 130 to the forwardly extending right angles ears 124 on the ends of the lever. The lower ends of the cords are provided with handles (not shown). When one of the cords is pulled downwards the lever is rocked in one direction and results in drive of the motor in one direction and concurrent release of the brake 20. When the other cord is pulled down-

wards the lever 120 is rocked in the reverse direction and results in reverse drive of the electric motor and concurrent release of the brake. When neither cord is subject to a downward pull the lever 120, due to the action of the helical spring 95 and the arm 96, assumes its neutral position wherein it extends transversely horizontally. The electric motor 16 operates so long as one of the cords 129 is pulled downwards. Release of the cord results in the reversing switch being automatically shifted into its neutral or "off" position and resultant stoppage of the motor and application of the brake 20.

The stop finger 128 which, as hereinbefore described, is fixedly connected to, and extends radially from, one end of the shaft 126 coats with a pair of stop pins 131 and 132 automatically to effect stoppage of the electric motor when the chain hook 70 is lowered or raised to a predetermined extent. The pin 131 is connected to the end of the chain 18 that is anchored and is adapted when the chain is payed out to a predetermined extent to strike against the finger 128 and cause the latter to rock or swing. Such movement on the part of the finger 128 operates through the medium of the shaft 126 the gear segments 122 and 123 and the rock shaft 80 to return the reversing switch to its neutral or "off" position. The other stop pin, i. e., the pin 132, is connected to the end of the chain having the hook 70 and is adapted when the hook end of the chain is drawn towards the sprocket to a predetermined extent to engage the finger 128 and swing the latter in such direction that it operates through the medium of the aforementioned parts to return the reversing switch to its neutral or "off" position.

In addition to the parts heretofore mentioned the hoist comprises a removable cup-shaped shell 133 for enclosing the housing 22, the reversing switch 19, the brake 20 and substantially all of the manually operable control mechanism 21. This shell is preferably in the form of a one-piece metal stamping and comprises a continuous side wall 134 and an end wall 135. The side wall is elliptical in cross section and has the free marginal portion thereof shaved to fit around the outer edge of the vertically extending inner wall 32 of the housing 22. When the shell 133 is in its operative position as shown in Figures 1, 2, 3, 5 and 6, the axis of the continuous side wall 134 extends horizontally and the end wall 135 is disposed outwards of the plate 83 having the extension 101. The shell is manipulated into its normal operative position by sliding it horizontally so as to bring the side wall 134 into encircling relation with the housing 22 and the other parts heretofore mentioned. In connection with sliding of the shell into place the side wall 134 is guided by the webs 40 and 41. Such webs serve in conjunction with the inner end wall 32 of the housing 22 to support the shell against lateral displacement. The shell end wall 135 has in the upper central portion thereof a hole 136 through which extends the outer end of the pin 125 when the shell is in place. In addition to the hole 136 the shell end wall has a pair of oppositely extending arcuate slots 137 through which extend the outer portions of the ears 124 at the ends of the lever 120 of the manually operable control mechanism 21. A disc-like cap 138 serves releasably to hold the shell 133 in its operative position. The central portion of the cap is connected to the outer end of the pin 125 by a conventional

bayonet catch 139. When it is desired to remove the shell 133 the cap 138 is turned or rotated sufficiently to release the bayonet catch. Thereafter the cap is removed so as to free the shell for outward sliding movement.

The herein described electric chain hoist effectively and efficiently fulfills its intended purpose and, due to the particular arrangement of its various component parts occupies but a comparatively small space. By reason of the fact that the electric motor 16 is located on one side of the frame 15 and all of the other parts, with the exception of the sprocket 17, the chain 18 and the hook 21, are mounted on the other side of the frame, the hoist, when supported by either of the two hooks is properly balanced without the necessity of employing any counterweight. By having the reversing switch 19, the brake 20 and the manually operable control mechanism 21 mounted all within the removable cup-shaped shell 23 such parts are readily accessible for inspection, repair or replacement purposes merely by removal of the shell. In view of the fact that the gearing between the sprocket 17 and the armature shaft of the electric motor is self-locking or irreversible as heretofore pointed out, there can be no displacement of any load on the hook 70 in the event of failure of the brake 20 or in the event that the brake is released while there is failure of supply of current to the electric motor.

The invention is not to be understood as restricted to the details set forth since these may be modified within the scope of the appended claims without departing from the spirit and scope of the invention.

Having thus described the invention, what we claim as new and desire to secure by Letters Patent is:

1. An electric chain hoist comprising a frame provided with upstanding means for attaching it to an overhead support and consisting of a vertically extending wall, a large sized upper arcuate side wall connected to one side of the vertically extending wall and arranged so that the ends thereof terminate but a comparatively small distance apart and are generally at the bottom, and a small sized lower arcuate side wall of less width than the upper arcuate side wall, connected to said one side of the vertically extending wall, disposed between the ends of the upper arcuate side wall and having its ends facing generally downwards, a housing connected to the other side of the vertically extending wall of the frame, a horizontal shaft extending through said vertically extending wall and having one end thereof disposed concentrically within the lower arcuate side wall and provided with a sprocket and its other end disposed within the housing, a chain trained around the sprocket, held on the sprocket by the aforesaid lower arcuate side wall and provided at one end thereof with load carrying means, an electric motor disposed adjacent said one side of the vertically extending wall and embodying a substantially cylindrical casing with one end thereof connected directly to the outer side margin of said upper arcuate side wall, and in addition a horizontal armature shaft having one end thereof extending through said vertically extending wall and into said housing, and gearing within the housing and between the two shafts for driving the sprocket from the motor.

2. An electric chain hoist comprising a frame consisting of a vertically extending wall, a com-

paratively wide large sized upper arcuate side wall connected to one side of the vertically extending wall and arranged so that the ends thereof terminate but a small distance apart and are generally at the bottom, and a comparatively narrow small sized lower arcuate side wall connected to said one side of the vertically extending wall, disposed between, connected to, the ends of the upper arcuate side wall and having its ends facing generally downwards, a swivel type hook adapted to suspend the hoist from an overhead support and having the shank thereof extending downwards through the top portion of the upper side wall of the frame, a housing connected to the other side of the vertically extending wall of the frame, a horizontal shaft extending through said vertically extending wall and having one end thereof disposed concentrically within the lower arcuate side wall and provided with a sprocket and its other end disposed within the housing, a chain trained around the sprocket, held on said sprocket by the aforesaid lower arcuate side wall, and provided at one end thereof with load carrying means, an electric motor disposed adjacent said one side of the vertically extending wall and embodying a substantially cylindrical casing with one end thereof connected directly to the outer side margin of said upper arcuate side wall and spaced outwards from the outer side margin of the lower arcuate side wall, and in addition a horizontal armature shaft having one end thereof extending through said vertically extending wall and into said housing, and gearing within the housing and between the two shafts for driving the sprocket from the motor.

3. An electric chain hoist comprising a frame provided with upstanding means for attaching it to an overhead support and embodying a vertically extending wall with a diagonally extending enlargement on one side thereof, a housing positioned adjacent said one side of the vertically extending wall and embodying a vertically extending inner end wall with a diagonal opening therein shaped conformably with the enlargement and in which the enlargement is seated, a horizontal shaft extending through that portion of the vertically extending side wall that embodies the lower end of the enlargement and having one end thereof disposed within the housing and its other end exteriorly disposed and provided with a sprocket, a chain trained around the sprocket and provided at one end thereof with load carrying means, an electric motor disposed adjacent and mounted on the other side of the vertically extending wall of the frame and having a horizontal armature shaft with one end thereof extending through the portion of said vertically extending wall that embodies the upper end of the enlargement and also extending into the housing, and gearing within the housing and between the two shafts for driving the sprocket from the motor.

4. An electric chain hoist comprising a cast metal frame provided with upstanding means for attaching it to an overhead support and consisting of a vertically extending wall with an integral diagonally extending enlargement on one side thereof, a large sized upper arcuate side wall connected to the other side of the vertically extending wall, positioned in substantially centered relation with the upper end of the enlargement, and arranged so that the ends thereof terminate but a comparatively small distance apart and are generally at the bottom,

and a small sized lower arcuate side wall connected to said other side of said vertically extending wall, positioned in substantially centered relation with the lower end of the enlargement, disposed between the ends of the upper arcuate side wall, and having its ends facing generally downwards, a housing disposed adjacent said one side of the vertically extending wall and embodying a vertically extending inner end wall with a diagonal opening shaped conformably to the enlargement and in which said enlargement is seated, a horizontal shaft extending through the portion of the vertically extending wall of the frame that has the lower end of the enlargement and having one end thereof disposed within the housing and its other end disposed concentrically within the lower arcuate side wall and provided with a sprocket, a chain trained around the sprocket and provided at one end thereof with load carrying means, an electric motor disposed adjacent said other side of the vertically extending wall of the frame and embodying a substantially cylindrical casing with one end thereof connected directly to said upper arcuate side wall, and in addition a horizontal armature shaft extending through the portion of the vertically extending wall with the upper end of the enlargement and into the housing, and gearing within said housing and between the two shafts for driving the sprocket from the motor.

5. An electric chain hoist comprising a cast metal frame consisting of a vertically extending wall with an integral diagonally extending enlargement on one side thereof, a large sized upper arcuate side wall connected to the other side of the vertically extending wall, positioned in substantially centered relation with the upper end of the enlargement, and arranged so that the ends thereof terminate but a comparatively small distance apart and are generally at the bottom, and a small sized lower arcuate side wall connected to said other side of said vertically extending wall, positioned in substantially centered relation with the lower end of the enlargement, disposed between the ends of the upper arcuate side wall, and having its ends facing downwards generally, a swivel type hook adapted to suspend the hoist from an overhead support and having the shank thereof extending downwards through the upper or top portion of the upper side wall, a housing disposed adjacent said one side of the vertically extending wall and embodying a vertically extending inner end wall with a diagonal opening shaped conformably to the enlargement and in which said enlargement is seated, a horizontal shaft extending through the portion of the vertically extending wall of the frame that has the lower end of the enlargement and having one end thereof disposed within the housing and its other end disposed concentrically within the lower arcuate side wall and provided with a sprocket, a chain trained around the sprocket and provided at one end thereof with load carrying means, an electric motor disposed adjacent said other side of the vertically extending wall of the frame and embodying a substantially cylindrical casing with one end thereof connected directly to said upper arcuate side wall, and in addition a horizontal armature shaft extending through the portion of the vertically extending wall with the upper end of the enlargement and into the housing, and worm and worm wheel variety gearing within said housing and between

the two shafts for driving the sprocket from the motor.

6. An electric chain hoist comprising a cast metal frame provided with upstanding means for attaching it to an overhead support and consisting of a vertically extending wall with an integral diagonally extending enlargement on one side thereof, a large sized upper arcuate side wall connected to the other side of the vertically extending wall, positioned in substantially centered relation with the upper end of the enlargement, and arranged so that the ends thereof terminate but a comparatively small distance apart and are generally at the bottom, and a small sized lower arcuate side wall connected to said other side of said vertically extending wall, positioned in substantially centered relation with the lower end of the enlargement, disposed between the ends of the upper arcuate side wall, and having its ends facing generally downwards, a housing disposed adjacent said one side of the vertically extending wall and embodying a vertically extending inner end wall with a diagonal opening shaped conformably to the enlargement and in which said enlargement is seated, a horizontal shaft extending through the portion of the vertically extending wall of the frame that has the lower end of the enlargement and having one end thereof disposed within the housing and its other end disposed concentrically within the lower arcuate side wall and provided with a sprocket, a chain trained around the sprocket and provided at one end thereof with load carrying means, an electric motor disposed adjacent said other side of the vertically extending wall of the frame and embodying a substantially cylindrical casing with one end thereof connected directly to said upper arcuate side wall, and in addition a horizontal armature shaft extending through the portion of the vertically extending wall with the upper end of the enlargement and into the housing, and irreversible gearing disposed within the housing, operative to drive the sprocket from the motor, and embodying a diagonal shaft extending at right angles to and between the armature shaft and the sprocket carrying shaft, a worm on the armature shaft, a worm wheel mounted on the upper end of the diagonal shaft and in mesh with the worm, a worm on the lower end of said diagonal shaft and a worm wheel mounted on said one end of the sprocket carrying shaft and in mesh with the last mentioned worm.

7. An electric chain hoist comprising a frame provided with upstanding means for suspending it from an overhead support and embodying a vertically extending wall, a housing connected to one side of the vertically extending wall and consisting of spaced apart inner and outer end walls and a continuous side wall between the end walls, a horizontal shaft extending through the vertically extending wall at a point beneath the suspending means, having one end thereof disposed in the housing and its other end exteriorly disposed and provided with a sprocket, a chain trained around the sprocket and provided at one end thereof with load carrying means, a reversible electric motor mounted on the other side of the vertically extending wall of the frame and having a horizontally extending armature shaft disposed above the sprocket carrying shaft and having one end thereof extending through said vertically extending wall and housing and of such length that its extremity terminates a small dis-

tance outwards of the outer end wall of the housing, gearing within the housing and between the two shafts for driving the sprocket from the motor, a reversing switch adapted to control the motor and mounted adjacent to, and outwards of, the continuous side wall of said housing, and a brake operative to brake the motor when the switch is in its neutral or "off" position, located directly outwards of the outer end wall of the housing and including a rotary element mounted fixedly on the extremity of said one end of the armature shaft.

8. An electric chain hoist comprising a frame provided with upstanding means for suspending it from an overhead support and embodying a vertically extending wall, a housing connected to one side of the vertically extending wall and consisting of spaced apart inner and outer end walls and a continuous side wall between the end walls, a horizontal shaft extending through the vertically extending wall at a point beneath the suspending means, having one end thereof disposed in the housing and its other end exteriorly disposed and provided with a sprocket, a chain trained around the sprocket and provided at one end thereof with load carrying means, a reversible electric motor mounted on the other side of the vertically extending wall of the frame and having a horizontally extending armature shaft disposed about the sprocket carrying shaft and having one end thereof extending through said vertically extending wall and housing and of such length that its extremity terminates a small distance outwards of the outer end wall of the housing, gearing within the housing and between the two shafts for driving the sprocket from the motor, a reversing switch adapted to control the motor and mounted adjacent to, and outwards of, the continuous side wall of said housing, a brake operative to brake the motor when the switch is in its neutral or "off" position, located directly outwards of the outer end wall of the housing and including a rotary element mounted fixedly on the extremity of said one end of the armature shaft, and a removable sheet metal cup-shaped shell extending around and serving to house said housing, switch and brake and arranged so that when it is in its normal position its end wall is outwards of the brake and the free margin of its side wall is disposed adjacent the inner end wall of the housing.

9. An electric chain hoist comprising a frame provided with upstanding means for attaching it to an overhead support having a housing at one side thereof, a horizontal shaft journaled on the frame beneath the attaching means and having one end thereof extending into the housing and its other end disposed exteriorly and provided with a sprocket for a hoisting chain, a reversible electric motor mounted on the other side of the frame having a horizontal armature shaft extending into the housing, gearing within the housing and between the two shafts for driving the sprocket from the motor, a reversing switch adapted to control the motor positioned normally in close proximity to one side of the housing, and a mounting for the switch embodying means whereby said switch may be swung bodily away from the housing into an inspection or maintenance position.

10. An electric chain hoist comprising a frame provided with upstanding means for attaching it to an overhead support having a housing at one side thereof, a horizontal shaft journaled on the frame beneath the attaching means and having one end thereof extending into the housing and

its other end disposed exteriorly and provided with a sprocket for a hoisting chain, a reversible electric motor mounted on the other side of the frame having a horizontal armature shaft extending into the housing, gearing within the housing and between the two shafts for driving the sprocket from the motor, a reversing switch adapted to control the motor positioned normally in close proximity to one side of the housing, a removable shell extending around and adapted to house the housing and switch, and a mounting for the switch embodying means whereby when the shell is removed said switch may be shifted laterally away from said one side of the housing into an inspection or maintenance position.

11. An electric chain hoist comprising a frame provided with upstanding means for normally suspending a hoist from an overhead support and having a housing, a horizontally extending shaft journaled on the frame beneath the suspending means and having one end thereof extending into the housing and its other end exteriorly disposed and provided with a sprocket, a reversible electric motor mounted on the frame, gearing in the housing for driving the sprocket from the motor, a horizontally extending anchor post mounted on the frame to one side of the sprocket, a roller chain trained around the sprocket and having a hoisting hook at one end thereof and its other

end pivotally connected to the anchor post by way of a pair of laterally spaced links, and a freely rotatable roller mounted on the anchor post between the links, disposed in alignment with the sprocket and arranged and adapted so that it serves in the event that the hoist is suspended by the chain hook instead of the suspending means to guide to or from the sprocket the portion of the chain that extends between the anchor post and the sprocket.
